WEATHERPROOF SOCKET FOR ELECTRIC LAMPS.

933,644.

Specification of Letters Patent. Patented Sept. 7, 1909.

Application filed June 1, 1908. Serial No. 435,972.

To all whom it may concern:

Be it known that I, GILBERT W. GOODRIDGE, a citizen of the United States of America, residing in the city of Bridgeport, in the county of Fairfield, in the State of Connecticut, have invented a certain new and useful Improved Weatherproof Socket for Electric Lamps, of which the following is a specification.

My invention relates particularly to that type of electric lamp sockets which are known as weatherproof bracket sockets, that is, sockets which are constructed for outdoor and weatherproof use and are to be secured 10 to pipes or other fixtures instead of being suspended by the conductor wires. Heretofore sockets of this type have been manufactured with the lead wires soldered to the two terminals of the lamp holder and passing 15 out through a hole or holes in the porcelain with insulation on the wires, insulating compound being poured in around the outwardly extending wires to make the interior weatherproof. When fixture men or 20 others wanted bracket sockets with extra long lead wires, they had to order them specially made up at the factory, and oftentimes, when they got the sockets where they were to be put up, the wiremen would find that 25 they had lead wires much longer than needed, and consequently there would be so much waste wire to be cut off and thrown away.

By my invention hereinafter described, 30 I am enabled to provide a bracket socket without lead wires and yet thoroughly weatherproof.

In the accompanying drawings Figure 1 is a section on the line 1—1, Fig. 3; Fig. 2 is a section on the line 2—2, Fig. 3; Fig. 3 is a plan view with the cap removed; Fig. 4 is a view of the cap; Fig. 5 is a perspective view of the back of the body of the 40 socket without its cap.

A is the cylindrical body of the socket made of porcelain or other suitable insulating material and adapted to receive within its open end the usual lamp receiving terminals consisting of the screw shell S and 45 central terminal C separated by the insulating button B, of porcelain or other suitable material. I form in the back end of this body A a central hole *a* and four smaller holes spaced around the central hole, and I 50 provide on the rear of the body two recesses

to receive brass or other metal terminal plates D, D, carrying binding screws *d*, *d*. These two plates are arranged over two diametrically opposite holes of the four mentioned, and these holes are of such a size as 50 to receive tubular rivets or eyelets *r*, *r*, Fig. 1, the ends of the rivets passing through corresponding holes in the terminal plates D, D, and retaining the plates fixed in their recesses, when the eyelet ends are flanged or 55 riveted to the plates or to the inner face of the body A. To the terminals S and C have been soldered the ends of wires 6, 7, and the opposite ends of these wires are inserted through the tubular rivets or eyelets *r*, *r*, 60 and soldered to their respective wire terminal plates D, D, Fig. 1. Insulating compound is now poured into the space back of 65 the lamp receiving terminals S, C, through the hole *a*, to make the socket water-proof. 70

The back of the socket is closed by a cap E of metal with the usual threaded nipple *e*, by which the socket may be screwed to a pipe or bracket. To the inner face of the cap I secure a paper or other suitable insulating lining *e*¹ which I extend well into the nipple *e*, so that the end of the pipe will be protected 75 from coming into contact with the wires. The cap is secured in place by screws 8, 8, passing through the cap from the back and 80 threaded into flanged bushings 9, 9, Fig. 2, in the back of the body A. A rubber gasket R is preferably fitted around the back of the body A, where the rim of the cap fits down 85 over it.

By the construction described, I have provided a weatherproof socket with outside terminal plates for ready attachment of the line wires, and dispensing with the customary lead wires projecting out through the 90 cement at the back.

I claim as my invention—

1. A weatherproof bracket socket, comprising an insulating body with lamp-holding terminals therein, terminal plates with binding screws on the back of the insulating body, an inclosing and supporting cap for the back of the socket, electrical connections from the lamp holding terminals to said plates, and insulating compound filling the 100 space in the body back of the lamp holding terminals.

2. A weatherproof bracket socket, comprising an insulating body with lamp-holding terminals therein, terminal plates with bind- 110

ing screws on the back of the insulating body, eyelets securing said plates in place, an inclosing and supporting cap for the back of the socket, wires connecting the lamp holding terminals to said plates through the eyelets and insulating compound filling the space in the body back of the lamp-holding terminals.

In testimony whereof I have signed my name to this specification, in the presence of 10 two subscribing witnesses.

GILBERT W. GOODRIDGE.
